[57] CLAIM

The ornamental design for the wagon, as shown and
described.

DESCRIPTION

FIG. 1 is a fragmentary perspective view of the front of
the wagon showing my new design;
FIG. 2 is a fragmentary perspective view of the rear of
the wagon;

FIG. 3 is a top view of the wagon;
FIG. 4 is a side view of the wagon;
FIG. 5 is a front view of the wagon;
FIG. 6 is a rear view of the wagon;
FIG. 7 is a bottom view of the wagon; and,
FIG. 8 is a sectional view of the wagon as seen along
the line 8—8 of FIG. 3.
The broken line showing of seat belts in FIGS. 1-3 are
for illustrative purposes only and form no part of the
claimed design.
